UNITED STATES PATENT OFFICE.

THOMAS RUTHERFORD MACMECHEN AND WALTER V. KAMP, OF NEW YORK, N. Y.

AIRSHIP.

1,238,316.

Specification of Letters Patent. Patented Aug. 28, 1917.

Application filed October 7, 1916. Serial No. 124,402.

To all whom it may concern:

Be it known that THOMAS RUTHERFORD MACMECHEN and WALTER V. KAMP, citizens of the United States, and residents of the 5 borough and county of Bronx, city and State of New York, have invented certain new and useful Improvements in Airships, of which the following is a specification.

This invention relates to improved means 10 for affording durable bearing surfaces between girder bars of wood, and metal compression posts or struts such as are described in our companion case Serial No. 121924, in airship frame structures, and our said improvement consists in the provision of metal 15 sleeves, rectangular in cross-section, which fit snugly within the apertures in the struts aforesaid, and themselves simply receive and incase a suitable lengthwise section of a girder bar, to afford extended, supporting bearings therefor.

The metal sleeves, which comprise sockets 20 for the girder bars, are secured within the metal struts by welding, brazing or soldering them thereto in their adjusted positions, or by otherwise connecting said elements; and the girder bars, which become incased by said sleeves, may be secured thereto, to prevent shifting longitudinally, by suitable 25 means, as by forming inturned teeth upon said sleeves, and causing said teeth to become firmly embedded in the material of said bars.

In the drawing:—

30 Figure 1 is a horizontal section of a strut, apertured to contain our improved bearing sleeves and the girder bars entered therein.

Fig. 2 is a partial, vertical section of the same, showing a longitudinal bar in cross- 40 section, and

Fig. 3 is a similar view, wherein the strut is positioned to show a longitudinal bar in longitudinal section.

In the example of our invention illustrated 45 herewith we have shown a tubular strut or radial compression member 1, having alined rectangular apertures 2 in its opposite walls, so as to contain a bar 3 of a longitudinal girder; said strut also having alined rectangular apertures 4 in its opposite walls, arranged transversely with relation to the axis through the apertures 2, so as to receive the opposed, meeting ends of bars 5, forming part of the transverse or hoop girders 50 of the air ship.

A metal sleeve 6, rectangular in cross section, and of suitable length, fits snugly within the apertures 2, intersecting the diameter of tube 1, and extending out beyond the walls thereof. Said sleeve is rigidly secured to said tube, as by welding, brazing or soldering it to the walls thereof, so that said sleeve becomes, to all intents and purposes, an integral part of the strut. The flanges 7, which may be spread out from the apertures 65 2 in the strut, in the formation of said apertures as pointed out in our said co-pending case Serial No. 121924, afford desirable points of contact with sleeve 6 for effecting the stated union between these members. 70

A bar 3 of a longitudinal girder, being now introduced within the sleeve 6, where it should have a close fit, thus receives an extended supporting bearing corresponding to the length of the sleeve. By this means the 75 surface of the bar 3, which, being of wood and therefore relatively soft, is free from the liability of becoming indented, and thus creating a loose joint, as might be the case if the girder bar surfaces were in direct im- 80 pinging contact, in the apertures 2, with the wall edges of the tubular strut. On the other hand, by the sleeved connecting means indicated, the joint is rendered rigid and durable, the contact being that of metal upon 85 metal, and the service and life of the joint are correspondingly increased.

To prevent lengthwise shifting of the bar 3 within the sleeve, the latter may have teeth, as 8, which may be struck from the material 90 thereof, and pressed inwardly, when the bar is within the sheath, to thereby enter and become embedded within the fiber of the bar material. Said teeth 8 may lie oppositely, the better to hold the bar against shifting 95 movement in both directions.

The hollow strut 1 may also have the opposite apertures 4 in its walls, arranged, in the instance shown, with their common axis transverse to the axis of apertures 2, and 100 intended for the reception, respectively, of the abutting ends of the bars 5, forming part of the polygonal or hoop girders employed in our stated airship frame construction.

Sleeves of metal, as 10, are employed to incase said bar ends, and to fit within the apertures 4, in manner similar to the disposition of sleeve 6 with respect to the apertures 2 and bar 3, and with the same objects 110

in view. The sleeves 10 may have the teeth 11, to prevent lengthwise shifting movement of the bars 5 in said sheaths.

Obviously the strut 1, which may be composed of several lengths, may be provided with only one or with a plurality of pairs of opposite apertures, this all depending upon the particular location of the strut length in the airship frame structure and the special 10 function it is to fulfil with relation to the girder bars and the radial support to be accorded the girders in the frame fabric.

We claim:—

1. The combination, with a hollow metal 15 compression member for airship frame construction, said member having opposite apertures in its walls, of a metal sheath fitted and secured within said apertures, said sheath lying across said member and 20 extending in opposite directions beyond its walls, to receive and form an extended bearing for a girder bar.

2. The combination, with a hollow metal 25 compression member for airship frame construction, said member having opposite apertures in its walls, of a metal sheath fitted and secured within said apertures, said sheath lying across said member and extending 30 in opposite directions beyond its walls, a girder bar fitted within said sheath, and

means for preventing lengthwise shifting of said bar in said sheath.

3. The combination, with a hollow metal compression member for airship frame construction, said member having opposite pairs 35 of apertures in its walls, whose axes intersect each other, of a metal sheath fitted and secured within one pair of said apertures, said sheath lying across said member and extending in opposite directions beyond its 40 walls; and a pair of metal sheaths, fitted, respectively, in the apertures of the other pair of apertures, in end abutting relation, respectively, with the first named sheath; said pair of sheaths, respectively, extending in 45 opposite directions beyond the walls of said member; said first named sheath, and said pair of sheaths, respectively, forming extended bearings for a longitudinal bar, and for the abutting ends of opposed hoop girder 50 bars.

Signed at the borough of Manhattan in the city, county and State of New York this 3rd day of October A. D. 1916.

THOS. RUTHERFORD MACMECHEN.
WALTER V. KAMP.
